UNITED STATES PATENT OFFICE

142,417

DESIGN FOR A PORTABLE BARBECUE OR SIMILAR ARTICLE

George W. Jones, Van Nuys, Calif., assignor to A. C. Mfg. Co., Van Nuys, Calif., a corporation of California

Application March 5, 1945, Serial No. 118,277

Term of patent 14 years

(Cl. D81—10)

To all whom it may concern:

Be it known that I, George W. Jones, a citizen of the United States, residing at Van Nuys, in the county of Los Angeles and State of California,
have invented a new, original, and ornamental
Design for Portable Barbecue or Similar Article, of which the following is a specification, reference
being had to the accompanying drawing, forming a part thereof.

Figure 1 is a front perspective view of a portable

barbecue or similar article, showing my new design.

Figure 2 is another perspective view of the portable barbecue of Figure 1, showing the back and opposite side thereof.

I claim:

The ornamental design for a portable barbecue
or similar article, substantially as shown.

GEORGE W. JONES.
